UNITED STATES PATENT OFFICE

130,657

DESIGN FOR A TYPEWRITER ERASER

Benjamin W. Hanle, Elizabeth, N. J., assignor to Eagle Pencil Company, New York, N. Y., a corporation of Delaware

Application April 18, 1941, Serial No. 100,486

Term of patent 14 years

To all whom it may concern:

Be it known that I, Benjamin W. Hanle, a citizen of the United States and residing at Elizabeth, in the county of Union and State of New Jersey, have invented a new, original, and ornamental Design for a Typewriter Eraser, of which the following is a specification, reference being had to the accompanying drawing, forming part thereof and in which

Fig. 1 is a front view of a typewriter eraser showing my new design,

Fig. 2 is a side view thereof,

Fig. 3 is a rear view thereof, and

Fig. 4 is a top edge view thereof.

I claim:

The ornamental design for a typewriter eraser, substantially as shown.
